2,430,302

CARRIER FOR BOTTLES AND OTHER ARTICLES

William A. Ringler, Wayne, Pa., assignor to The Gardner-Richardson Company, Middletown, Ohio, a corporation of Ohio

Application October 4, 1944, Serial No. 557,081

8 Claims. (Cl. 224—45)

1

My invention relates to carriers, and in particular to sling-type carriers having end-wall straps. One kind of such carriers is described in Patent 2,335,197, in my name, issued November 23, 1943. A principal object of this invention is the provision of improvements in structures of this class.

A more specific object is the provision of a knocked-down or collapsible carrier of which all wall parts are attached together in the structure as manufactured and shipped, obviating the shipment and use of separated wall parts and their interfitting during the operation of setting up the carrier.

Another object is the provision of a collapsible carrier which is simpler and easier to erect.

Yet another object of the invention is the provision of a carrier which, when erected, is characterized by greater stability, and which will maintain its erected condition whether filled or empty.

These and other objects of the invention which will be pointed out hereinafter, or will be clear to one skilled in the art upon reading these specifications, I accomplish by that construction and arrangement of parts of which I shall now describe an exemplary embodiment. Reference is made to the drawings forming a part hereof and wherein:

Figure 1 is a plan view of a body blank for my structure.

Figure 2 is a partial plan view showing the folding of top portions of the side walls for reinforcement.

Figure 3 is a plan view showing the attachment of the end strap members.

Figure 4 is an elevational view of one type of handle member which may be employed.

Figure 5 is a plan view of an end strap member.

Figure 6 shows one form of the collapsed structure.

Figure 7 shows in plan a step incident to erection.

Figure 8 is a perspective view showing the erected structure.

The body blank is an elongated piece of box board or other suitable flexible material indicated at 1 in Figure 1. Centrally of the blank a pair of score lines 2 and 3 demarcate a bottom wall 4 from side wall members 5 and 6.

The blank as shown is rectangular in general configuration; and the outer ends of the side wall members are provided with diagonal score lines 7 and 8 or 9 and 10. These score lines permit triangular portions 5a and 5b or 6a and 6b, of the

2

side walls to be folded over, as shown in Figure 2.

The precise angularity of the diagonal score lines is not a limitation and will be governed by the desired shape and height of top portions of the side walls. It may be preferred, as shown, to cause these score lines to meet at a point inwardly of the extreme ends of the blank and to notch the blank to meet the juncture of the score lines as indicated at 11 and 12. The purpose of this is to provide an overlap of the triangular portions when folded as shown in Figure 2. This overlap may be employed with a suitable application of adhesive to secure the triangular folded portions in place. As set forth hereinafter, however, other means may be used with or without adhesive union.

The total effective height of the side wall members will be chosen so as to be appropriate to the articles to be carried, as will the general dimensions of the wall portions of the structure. If the carrier is to be used for bottles, the choice of an overall height for the side walls which is not greater than the height of the bottles will permit the stacking of filled carriers.

25 To permit collapsing, I provide the bottom wall panel 6 with a central score line 13.

Notches 14 are provided in the side edges of the side walls preferably slightly inwardly of the termination of the diagonal score lines. These notches serve as retaining means for end wall straps hereinafter to be described. Consequently, the length of these notches will be such as to accept the end wall straps snugly, i. e., the length of the notches will preferably be approximately the same as the width of the end wall straps. The notches themselves will be spaced from the edges of the bottom wall panel sufficiently to enable the end wall straps efficiently to retain articles in the carrier.

30 An end wall strap is indicated at 15 in Figure 5. It is an elongated and narrow strip of box board or other flexible material, preferably provided with a central transverse score line 16 and other outlying score lines 17 and 18 which in the completed and erected structure will fall at approximately the points where the end wall straps engage in the notches 14.

Sling type bottle carriers have heretofore been provided with end wall straps; but these straps have either been separate elements which had to be engaged with the side walls, as by inserting locking tongues in slits in the side walls, or else they have been formed from the side walls themselves, thereby weakening the side walls. I have found that it is possible to provide end wall strap

members in a sling type carrier and by proper selection of the various dimensions, attach these end straps to the side walls pivotally, but permanently, to obtain a structure which is both collapsible and easy to erect.

When the blanks have been formed, the first operation is the folding and securing of the triangular side wall members as has already been described in part and illustrated in Figure 2. The triangular portions may be adhesively secured to each other or to the side walls or both. Where a handle member such as that hereinafter described is to be used, it is convenient to provide a grommet 19 near the apex of the folded side walls. This not only serves to receive the hook like ends of a ball-like handle formed in part at least of wire, but it may also be the means for securing the triangular portions in folded condition.

As a next step, as illustrated in Figure 3, two of the strap members 15 in superposed condition are placed upon the body blank 1 and are pivotally fastened to it at points 20 and 21. This fastening is conveniently done by means of grommets; but it may be accomplished by any suitable means productive of a pivotal connection. The position of the pivot points 20 and 21 is important. The end wall width of the erected carrier will of course be the same as the width of the bottom wall 4; but it is necessary that the pivot point 20 not only lie midway between the notches 14 in the side wall 5, but also that the distance between the pivot point 20 and the edge of the bottom wall be the same as the distance between the pivot point 20 and the bottom of either notch 14. Actual distances will vary of course, with the size and shape of different carriers; but by varying the distance of the notches 14 from the edges of the bottom panel the requirements set forth above can readily be met in bottle carriers and in carriers for most articles. One reason for the noted requirements is that when they are met, the strap members 15 will lie flat upon the flat body blank as shown in Figure 3.

In carriers which are very long in relation to their height, it is convenient to mark or perforate both the body blank and the strap members and to employ strap members in which the length between the pivot points 20 and 21 is not the same as the corresponding length between the same points on the body blank. In this event, the straps must be attached to the body blank when the blank is in other than a flat condition. But where the distance between the pivot points 20 and 21 is the same both for the body blank and the straps, the operation of attaching the straps is conveniently performed by a simple mechanism having a work table with means for positioning the body blanks and a pair of grommeting devices permanently located so as to apply grommets at points 20 and 21. The straps 15 are then superposed and placed on the body blank in such position that they will be caught by the grommets. No marking is necessary.

The structure thus produced may be folded over as shown in Figure 6, the body blank bending on score line 13 and the straps bending on score lines 16. If there is binding, the bottom panel may be collapsed inwardly while the straps are collapsed outwardly. The illustrated knocked down structure of Figure 6 is a convenient one for shipment and storage.

When it is desired to erect the structure, the pivoted straps are swung oppositely and positioned in alignment with the notches 14 as shown in Figure 7. When the side wall members are

drawn apart with a concurrent flattening of the bottom wall and of the central portions of the end wall straps which now bend on score lines 17 and 18. This provides a structure as shown in Figure 8.

A handle such as shown in Figure 4 may then be attached to the structure. The handle comprises a wire member 22 with a cylindrical handle part 23 over the grip portion. The ends of the wire are bent to form hooks 24 and 25 which can be engaged in the grommets 19 and 19a as shown.

My structure is not limited to the use of such a handle. Strap-like handles of box board or other material may be provided with means for engagement with the reinforced upper portions of the side walls. Handles of box board, woven or braided tape, heavy cord or the like may be attached to the reinforced portions of the side walls. This may be done during the manufacture of the carrier and after it has been collapsed as in Figure 6, giving a complete structure with no unattached parts.

Modifications may be made in my invention without departing from the spirit of it.

Having thus described my invention in an exemplary embodiment, what I claim as new and desire to secure by Letters Patent is:

1. In a structure of the class described, a body blank having a central bottom wall panel and outlying side wall panels erectable with respect to the bottom wall panel, and a pair of strap members pivoted to the side wall panels at points spaced from the edges of the bottom wall panel and intermediate the edges of the said side wall panels, the said strap members having central portions equivalent in length to the width of the bottom panel and outlying portions of a length to extend to the said pivot points when said strap members are erected to form end wall straps for the structure.
2. The structure claimed in claim 1, wherein the said straps are superposed and wherein the distance between the said pivot points is the same for said straps and for the body blank.
3. The structure claimed in claim 1, wherein the said straps are superposed and wherein the distance between the said pivot points is the same for said straps and for the body blank, and wherein the side edges of the said side walls are notched to accept said straps in the erected structure, the said pivot points being located midway between said notches.
4. The structure claimed in claim 1, wherein the said straps are superposed and wherein the distance between the said pivot points is the same for said straps and for the body blank, and wherein the side edges of the said side walls are notched to accept said straps in the erected structure, the said pivot points being located midway between said notches.
5. In a bottle carrier or the like, an elongated box board blank, cut and scored to provide a central bottom wall panel and outlying side wall panels, a pair of strap members in superposed position lying centrally and longitudinally of said blank, the said strap members being conjointly grommeted to said side walls at points equidistant from the side edges of said bottom panel and the edges of said side wall panels.
6. In a bottle carrier or the like, an elongated box board blank, cut and scored to provide a central bottom wall panel and outlying side wall panels, a pair of strap members in superposed

70
75

position lying centrally and longitudinally of said blank, the said strap members being conjointly grommeted to said side walls at points equidistant from the side edges of said bottom panel and the edges of said side wall panels, the said structure being collapsed on a score line intermediate the side edges of the bottom panel and on score lines intermediate the ends of said straps.

7. The structure claimed in claim 6, in which the edges of said side walls are notched to receive said straps.

8. The structure claimed in claim 6, in which the edges of said side walls are notched to receive said straps, and in which outer triangular corner portions of said side walls are folded over

to provide reinforcements and grommeted for the reception of a handle member.
